(57) **CLAIM**

The ornamental design for a filter housing, as shown and described.

DESCRIPTION

FIG. 1 is a front perspective view of a filter housing of the pneumatic patient circuit in accordance with our design; FIG. 2 is a front elevation view of the filter housing of FIG. 1;

FIG. 3 is a rear elevation view of the filter housing of FIG. 1;

FIG. 4 is a first side elevation view of the filter housing of FIG. 1;

FIG. 5 is a second side elevation view of the filter housing of FIG. 1;

FIG. 6 is a top plan view of the filter housing of FIG. 1; FIG. 7 is a bottom plan view of the filter housing of FIG. 1; and,

FIG. 8 is a front perspective view of the filter housing of FIG. 1;

The broken lines shown in FIG. 3 depict unclaimed portions of the filter housing and the broken lines shown in FIG. 8 are included for the purpose of illustrating environmental subject matter and form no part of the claimed design.

1 Claim, 5 Drawing Sheets
